R. J. PIERSOL ET AL

ORE SEPARATOR

Filed May 15, 1920

UNITED STATES PATENT OFFICE.

ROBERT JAMES PIERSOL, OF HOUSTON, AND ALBERT DOWLER RILEY, OF CRAFTON, PENNSYLVANIA, ASSIGNORS TO STANDARD CHEMICAL COMPANY, OF PITTSBURGH, PENNSYLVANIA.

ORE SEPARATOR.

Application filed May 15, 1920. Serial No. 381,658.

To all whom it may concern:

Be it known that we, ROBERT J. PIERSOL and ALBERT D. RILEY, citizens of the United States, and residents of Houston and 5 Crafton, in the counties of Washington and Allegheny, respectively, and State of Pennsylvania, have invented certain new and useful Improvements in Ore Separators; and we do hereby declare the following to 10 be a full, clear, and exact description of the invention, such as will enable others skilled in the art to which it appertains to make and use the same.

This invention relates to improvements 15 in ore separators and more particularly to a machine for liberating value-bearing constituents from the gangue of ore when said gangue consists of sand grains,—the object of the invention being to provide a machine 20 for the purpose stated which will operate to cause removal of the value-bearing constituents from the sand grains by shearing.

A further object is to provide simple and 25 efficient means of adjustment whereby the most effective shearing of the ore under treatment shall be insured.

With these and other objects in view, the 30 invention consists in certain novel features of constructions and arrangements of parts as hereinafter set forth and pointed out in the claims.

In the accompanying drawings; Figure 1 is a longitudinal sectional view, and Figure 2 is a transverse sectional view of a machine 35 illustrating our invention.

In the concentration of ores in which that portion which embodies the value-bearing constituents is soft and the gangue portion composed of sand particles,—such ore for 40 example, as carnotite,—it is a matter of considerable importance that the sand particles shall not be crushed because of the difficulty and expense of eliminating silica which might otherwise be mixed with the value 45 bearing constituents, in subsequent treatment of the latter to recover the values. We have found by experience that the soft value-bearing constituents (which in carnotite ore is in a condition of impalpable 50 comminution) can be most effectually and completely separated from the sand grains by a process of the shearing of the sand grains against each other. After the soft value-bearing constituents of the ore shall 55 thus have been removed or detached from

the sand particles, said constituents may be separated from the sand or gangue by either a wet or a dry method of classification, as by washing the values from the sand grains by a water process, or by separating dust values 60 from the sand grains by vacuum in a dry process.

Heretofore, concentration of ore has been obtained by the compression of the ore between heavy mullers and a plate or surface 65 on which the mullers roll, thus crushing the gangue portion as well as the softer value-bearing portion, but by the shearing method of separation, we are able to obtain a higher 70 degree of concentration because liability of crushing and hence the comminuting of the sand grains is reduced to a minimum and the silicious constituents of the ore can therefore be prevented from escaping with the values 75 during the process of wet or dry classification. Furthermore the shearing method of removing the value-bearing constituents from the sand gives higher grade of extraction of values because the shearing insures a greater and more complete liberation of 80 value-bearing constituents of the ore from the sand grains than can be obtained by compression or grinding of the ore.

In the drawing, we have illustrated a machine whereby the value-bearing constituents of ore, such as carnotite ore, may be effectually removed by shearing, from the sand gangue grains, and which will operate effectually to treat ore containing a high 85 percentage of moisture, thus eliminating the 90 necessity for the use of a dewatering device previous to the concentration in a commercial plant.

In the embodiment of our invention shown in the drawing; 1 represents a cylinder through which a revoluble shaft 2 passes, suitable bearings 3, 3 being provided for said shaft, and the latter carries a pulley 4 to receive a driving belt from any convenient 95 source of power. The cylinder 1 may be made in sections bolted together so that it may conveniently be made of any desired length to accommodate any desired number 100 of units of the operating mechanism herein- after described,—said cylinder being provided at one end with a hopper 5 into which the ore may be deposited and by which it will be directed into the cylinder, and at the other end of the cylinder, a discharge spout 105 6 is provided.

It may here be stated that ores as they are mined often include lumps of considerable size. This is true of carnotite ore and these lumps must be reduced. We therefore 5 crush the ore before discharging the latter into the hopper 5, but this crushing is such as to disintegrate the lumps without crushing the sand particles.

Each unit of the machine comprises a 10 spider 7 keyed or otherwise rigidly secured to the shaft 2, and a plurality of shearing blades 8,—said spider being provided with arms 9 and pairs of lugs 10 with which the blades are connected. Each shearing blade 15 is made in the form of a curved plate provided at one end with an arm 11 adjustably attached to one of the arms 9 of the spider by a pin-and-slot connection as indicated at 12.

At the other end of each blade, two 20 pairs of lugs 13 are located and these are adjustably connected with the lugs 10 of the spider through the medium of turnbuckles 14 and rod sections 15. The blades 8 are so disposed at an angle to the wall of 25 the cylinder that each blade will form, with the wall of the cylinder, a wedge-shaped space such as shown at 16, so that as the blades revolve, the ore will be sheared between said blades and the wall of the cylinder. The adjustability of the blades and hence the adjustability of the wedge-shaped spaces between said blades and the wall of 30 the cylinder, is a matter of importance, as the amount of shearing of the ore depends 35 both on the size of the space or opening at 17 and the angle between the blade relatively to the cylinder or casing which may be controlled by adjusting the leading end 18 of the blade. The blades may be ad- 40 justed as best suited to produce the most efficient shearing of the particular batch of ore to be treated.

The ore, previously crushed to reduce the lumps to proper size and containing a desired percentage of moisture will be fed into the hopper 5, and the ore will pass progressively through the several units (any desired number of units being provided to insure removal of a maximum amount of 45 value-bearing constituents from the sand 50 grains) and the sheared ore will be discharged through the spout 6. The ore thus discharged will be subjected to a suitable

hydraulic or a dry classifier for separating the value-bearing constituents from the sand 55 grains.

Having fully described our invention what we claim as new and desire to secure by Letters-Patent, is:—

1. A machine for removing pulverulent value-bearing constituents from sand gangue, comprising a container having a smooth inner face, a revoluble shaft, a member carried by said shaft and having normally fixed relation thereto, said member 60 having a smoother curved working face spaced at all points from the smooth inner face of the container and so disposed relatively to said inner face as to provide a continuously moving wedge-shaped space open 65 at both ends.

2. A machine for removing pulverulent value-bearing constituents from sand gangue, comprising a container having a smooth inner face, a revoluble shaft, a plurality of members carried by said shaft and having normally fixed relation thereto, said members having smooth curved working 70 faces permanently spaced at all points from the smooth inner face of the container, and so disposed relatively to said inner face as to provide continuously moving wedge-shaped spaces open at both ends.

3. A machine for removing pulverulent value-bearing constituents from sand 75 gangue, comprising a container having a smooth inner face, a revoluble shaft, a plurality of members normally fixed to said shaft and having curved smooth faces forming with the inner face of said container a 80 series of wedge-shaped spaces open at both ends, said members normally revolvable in a circular path, and means for adjusting said members to adjust the form of said wedge-shaped spaces.

In testimony whereof, we have signed this specification in the presence of the subscribing witnesses.
